PACKAGING MACHINE

Thomas E. Dugle, Indian Hill, and Roland W. Wagner, Sharerville, Ohio, assignors, by mesne assignments, to Warrick Equipment Corp., Cincinnati, Ohio, a corporation of Ohio

Filed June 5, 1961, Ser. No. 115,041
16 Claims. (Cl. 53—62)

This invention relates to packaging machinery. More particularly, this invention relates to a machine for packaging articles in groups.

An object of this invention is to provide a machine which counts a predetermined number of articles and groups the articles for packaging.

A further object of this invention is to provide a machine which places groups of articles of predetermined size in wrappers.

A further object of this invention is to provide a machine of this type which can handle a large number of cylindrical articles at high speed and in which the articles are arranged in banks or groups one on top of another.

A further object of this invention is to provide a machine of this type in which the articles are advanced first into one bin or tray and then into another bin or tray and in which an article diverting device is moved in response to the count of articles for diverting a predetermined number of articles into each tray.

A further object of this invention is to provide a machine of this type in which the cylindrical articles are advanced between spaced belts to pass an article counting device and in which, after the articles have passed the counting device, the belts diverge toward the trays into which the articles are advanced after counting of the articles and in which a diverter roller is mounted between the diverging portions of the belts, the roller being advanceable crosswise of the direction of article movement between the belts to divert the articles in alternate directions and into either of the pair of trays.

A further object of this invention is to provide a machine of this type in which the trays are mounted one above the other so that groups of articles are segregated one above another.

A further object of this invention is to provide a machine of this type in which the diverter roller is mounted for rotation and that means is provided for rotating the diverter roller and reversing the direction of diverter roller rotation when the roller is moved from one of its positions to the other of its positions.

Another object of this invention is to provide a machine of this type in which the articles advance longitudinally between the belts and into the trays, the trays being generally in alignment with the course of the articles between the belts and in which the articles are then advanced axially by rams which move through the trays to move the articles from the trays into package holding receptacles or buckets.

A further object of this invention is to provide a machine of this type in which the rams are moved alternately through one tray and then through the other so that, while a ram is moving through one of the trays, the other tray is being filled and, after the other tray is filled, the action is reversed so that the articles in the other tray are advanced axially while the first mentioned tray is filling.

A further object of this invention is to provide such a machine in which the articles are advanced axially into a package holding bucket and in which means are provided for folding a wrapper and for positioning the wrapper in the package holding bucket embracing the articles.

A further object of this invention is to provide a machine of this type in which a wrapper is folded into a

2

receptacle adjacent the package holding bucket and opposite the trays, and in which, thereafter, the wrapper is advanced into the bucket in a direction axially of the articles by a card ram, and a lower article ram moves 5 articles into the wrapper in a direction opposite to that in which a wrapper moving or card ram advances.

A further object of this invention is to provide a machine of this type in which the wrapper is folded to a U-shape inside a wrapper folding frame adjacent a bucket loading station, in which the bucket is of generally U-shape with one wall of the bucket being swingable outwardly, in which means is provided for swinging said wall of the package holder or bucket to open position as the wrapper is advanced into the bucket and articles are being 10 moved into the wrapper in the package holder, and in which means is provided for swinging said wall to a closed substantially upright position when the package holder and articles are moved away from the loading station.

A further object of this invention is to provide a machine of this type in which the articles are delivered to the belts by an article conveyor having a curved portion adjacent the belts from which the articles advance to between the belts and in which means is provided for swinging a portion of at least one of the belts adjacent 15 the article conveyor between an open position in which there is sufficient space between said one of said belts and the article conveyor to permit an article to enter the space between the belts and a closed position in which adjacent belt courses are substantially parallel and sufficiently closely spaced so that each article is firmly gripped by the belts after leaving the article conveyor.

A further object of this invention is to provide a machine of this type in which articles are delivered to the article conveyor by an input conveyor having upright 20 parallel spaced cooperating courses adapted to grip cylindrical articles therebetween.

A further object of this invention is to provide such a machine in which there is a discharge space below and between the cooperating courses and that means is provided for diverting articles into said space.

A further object of this invention is to provide a machine of this type in which oscillating side guides are disposed parallel to and on opposite sides of the article conveyor, in which the input conveyor delivers the articles into the space between the oscillating side guides and in which the side guides centrally position the articles for proper delivery to the belt conveyor which receives the articles from the article conveyor.

A further object of this invention is to provide means for engaging any article which comes to rest above two articles already on the article conveyor to roll such article into position directly on the article conveyor so that only a single layer of articles is disposed on the article conveyor when delivered to the belt conveyors.

A further object of this invention is to provide a machine of this type which is adapted to count and package cylindrical articles and food products such as sausages, wieners and the like, and is adapted to handle 50 such cylindrical articles when delivered thereto either rapidly or at intervals, and accurately and quickly segregates the articles in groups containing a predetermined number of the articles in packages and delivers such packages for further handling.

The above and other objects and features of the invention will be apparent to those skilled in the art to which this invention pertains from the following detailed description and the drawings, in which:

FIG. 1 is a view in front elevation of a machine for packaging articles constructed in accordance with an embodiment of this invention;

FIG. 2 is a plan view of the machine illustrated in FIG. 1;

FIG. 3 is an enlarged plan view of an input conveyor and a portion of an article conveyor which form a part of the machine shown in FIGS. 1 and 2, parts thereof being broken away to reveal structural details, wiener sausages being carried by the machine being shown in dot-dash lines, a fragmentary portion of a peeler conveyor being shown in association therewith;

FIG. 4 is a view in side elevation of the input conveyor illustrated in FIG. 3, the framework of an article conveyor being shown in section, a shaker frame being shown in an alternate position in dot-dash lines;

FIG. 4A is a view in section taken on the line 4A—4A in FIG. 3;

FIG. 4B is a view in section taken on the line 4B—4B in FIG. 4;

FIG. 5 is an enlarged fragmentary view in front elevation showing details of construction of a portion of the article conveyor, and shaker frame illustrated in FIGS. 3 and 4 also showing article wiping plates forming a portion of the machine;

FIG. 6 is a plan view of the article wiping plates and of the portion of the article conveyor and the shaker frame illustrated in FIG. 5;

FIG. 7 is an enlarged view in front elevation showing a loading station of the machine illustrated in FIGS. 1 and 2 and a discharge station thereof, the machine being broken away therebetween;

FIG. 7A is a view in vertical section showing article receiving trays at the loading station, the trays being shown swung open;

FIG. 8 is a plan view of the portions of the machine shown in FIG. 7;

FIG. 9 is a broken away view in side elevation of a main housing beneath the loading station, the walls of the housing and portions of the machinery thereinside being broken away and in section to reveal structural details, fragmentary portions of the machine thereabove being shown in association therewith;

FIG. 9A is a view in front elevation of a portion of the machinery illustrated in FIG. 9 looking in the direction of the arrows 9A—9A in FIG. 9;

FIG. 10 is a somewhat schematic broken away view in front elevation of the main housing with portions of the walls thereof being broken away, drive chains and sprockets thereof being shown in dashed lines;

FIG. 11 is a view in front elevation of a belt conveyor and a gear housing which form a portion of the machine illustrated in FIGS. 1 and 2;

FIG. 12 is an enlarged perspective view of the belt conveyor and gear housing, portions thereof being broken away and in section to reveal structural details;

FIG. 13 is an enlarged perspective view of the gear housing, portions thereof and of gears and shafts and other mechanism thereinside being broken away to reveal structural detail, openings in a wall thereof being omitted;

FIG. 14 is a view in side elevation of the gear housing illustrated in FIG. 13 with portions broken away to reveal structure of apparatus for operating a bell crank and reversible diverter roller support which form a portion of the machine, openings in a front wall of the gear housing being omitted;

FIG. 15 is a view in front elevation of the gear housing shown in FIGS. 13 and 14 with portions broken away to reveal construction of a drive for a swinging belt-supporting roller which forms a part of the machine, openings in a front wall of the gear housing being omitted;

FIG. 16 is a perspective view of the gear housing illustrated in FIGS. 13, 14 and 15 looking from the rear side thereof, a portion thereof being broken away to reveal structural details;

FIG. 17 is a perspective view of the interior of a portion of the main housing and article advancing rams and ram driving apparatus, portions of the housing, and of a ram supporting unit being broken away to reveal structural details, the rams and drive cams therefor being shown out of synchronization to show both rams partially advanced;

FIG. 17A is a fragmentary view in transverse section showing details of construction of a shaft restraining brake which forms a portion of the ram operating structure illustrated in FIG. 17;

FIG. 17B is a view in horizontal section showing details of construction of the brake illustrated in FIG. 17A;

FIG. 17C is a fragmentary view in side elevation showing details of the ram mounting and ram operating and guiding devices;

FIG. 17D is a top plan view of the rams, ram supporting structure, and tray structure illustrated in FIG. 17C taken on the line 17D—17D in FIG. 17C;

FIG. 18 is a perspective view of portions of a card storage and card delivery apparatus adjacent the loading station, the drive thereof being shown in association therewith;

FIG. 19 is a fragmentary perspective view of card folding mechanism of the machine;

FIG. 19A is a fragmentary view in side elevation of a portion of the card delivering apparatus, a card operating cable and pulley therefor being omitted;

FIG. 19B is a plan view of the portion of the machine illustrated in FIG. 19A;

FIG. 19C is a view in section taken on the line 19C—19C in FIG. 19B;

FIG. 19D is an enlarged view in section taken on the line 19D—19D in FIG. 19C;

FIG. 20 is a perspective of a portion of the main housing with the housing wall and portions of the mechanism being broken away to reveal details of structure of a package conveyor driving mechanism;

FIG. 20A is a fragmentary view in side elevation of a portion of the main housing, parts being broken away to reveal structural details of rams, trays, package conveyor, and card ram and card ram drive, the card ram being shown in fully advanced position in full lines and in retracted position in dot-dash lines;

FIG. 21 is a fragmentary view in side elevation similar to FIG. 20A but showing the lower ram advanced, with unrelated parts being omitted;

FIG. 22 is a perspective view of a card storage bin which forms a part of the machine, a card folding member being shown in association therewith;

FIG. 23 is an enlarged view in upright section showing the card folding members and associated card folding apparatus, the card folding member and cards being shown in full lines in fully folded position, in triple dot-dash lines in position before folding, and in double dot-dash lines in partly folded position;

FIG. 24 is a view in vertical section taken through the card storage bin shown in FIG. 22, cards being shown in position thereinside, a vacuum cup assembly and a card folder being shown in card released position in double dot-dash lines, and in an intermediate position in full lines, the vacuum cup assembly being shown in card engaging position in dot-dash lines;

FIG. 25 is a fragmentary view in section taken on a line 25—25 in FIG. 23;

FIG. 26 is a plan view of a wrapper card used in the machine, score lines being shown in dot-dash lines, a rectangular card used in the machine being shown in dashed lines in association therewith;

FIG. 27 is a view partly in section and partly in side elevation of an electromagnetic clutch and brake unit which forms a part of the machine;

FIG. 28 is a diagrammatic view of the electrical circuit of the machine;

FIG. 29 is a cycle diagram showing operation of the machine; and

FIG. 30 is a plan view of a package of wieners as delivered by the machine.

In the following detailed description and the drawings, like reference characters indicate like parts.

Introduction

In FIGS. 1 and 2 is shown a machine 9 for counting and packaging articles which is constructed in accordance with an embodiment of this invention. The machine is constructed for counting and packaging wiener sausages or the like and placing same in packages containing a predetermined number of articles (ten) in each package with two layers mounted one on top of the other, each layer containing half of the articles.

The machine includes a main housing 10 and a main frame 12 which support an article conveyor 13. Wieners 14 (FIG. 3) are fed to the article conveyor 13 by input conveyors 15 (FIGS. 1, 2, 3, and 4) which receive the wieners from peeling machines or the like (not shown). Peeling machine conveyors 15a (FIGS. 3 and 4) deliver the wieners to the input conveyors. After being delivered to the article conveyor by the input conveyors, the wieners are carried to the left as shown in FIGS. 1 and 2, by the article conveyor 13 to a belt conveyor 16 mounted on the housing 10. A package feeding conveyor 17 is also mounted on the housing 10 and frame 12. The package feeding conveyor 17 carries a plurality of buckets 18. Wrapper cards 19 (FIG. 2) are fed from a card holder 21 to the buckets, and wieners from the belt conveyor 16 are counted and advanced into the buckets in a sequence determined by the count so that a predetermined number of wieners are received in a wrapper card in each bucket.

Input conveyors

The wieners enter the machine on the input conveyors 15. Details of construction of one of the input conveyors are shown in FIGS. 3 and 4. The input conveyor 15 includes a main frame plate 22. Spaced idle rollers 23 and 24 are rotatably mounted at one end of the main frame plate 22. The idle roller 23 is mounted on a shaft 26 carried by bearings (not shown in detail) in the main frame plate 22 and in a bracket 27 attached thereto. The idle roller 24 is mounted on a similar shaft 28 mounted in bearings carried by the main frame plate 22 and by a bracket 29 attached thereto. Spaced drive rollers 31 and 32 at an inner end of the main frame plate 22 are mounted on shafts 33 and 34, respectively. Shafts 33 and 34, as shown in FIG. 4B, are rotatably mounted in a frame member 36. The frame member 36 is attached to an article conveyor frame 38 (FIG. 4) which, in turn, is attached to the main frame 12.

Lower ends of the shafts 33 and 34 carry bevel gears 39 and 41 (FIG. 4B) which mesh with bevel gears 42 and 43, respectively, mounted on an input conveyor drive shaft 44. The shaft 44, in turn, is driven by a sprocket 45 mounted thereon. A drive chain 45a (FIG. 4) runs on the sprocket 45 and on a sprocket 45b (FIG. 4). The sprocket 45b, in turn, is mounted on a shaker drive shaft 45c. The shaker drive shaft 45c is driven by operation of a motor 46 (FIG. 1). Gears (not shown) in a gear box 46a (FIG. 2) driven by the motor 46 drive sprocket 47. A chain 48 is driven by the sprocket 47. The chain 48 in turn drives a sprocket 49 mounted on a side shaft 50. A sprocket 50a mounted on the side shaft 50 drives a chain 50b which runs on a sprocket 50c (FIG. 1). The sprocket 50c is mounted on the shaker drive shaft 45c so that operation of the motor 46 drives the shaker drive shaft 45c.

Input conveyor belts 51 and 52 are mounted on and run on rollers 23-31 and 24-32, respectively (see FIG. 3). Idle rollers 53, mounted on shafts 54 (FIG. 4A) supported by back-up frames 55, keep inner courses 56

and 57 of the belts 51 and 52, respectively, substantially parallel and properly spaced to grip the wieners. The back-up frames 54 are attached to the main frame plate 22 in an appropriate manner, not shown.

5 The main frame plate 22 is supported by the frame member 36 and by a support leg 59 (FIG. 4) which can rest on an appropriate support 61.

10 Wieners reach the conveyor belts 51 and 52 from the peeler conveyor 15a which may be a part of the conventional wiener peeling device (not shown in detail).

15 Wiener conveyor belt courses 56 and 57 of the input conveyor belts are sufficiently spaced to grip the wieners 14, and the wieners 14 are supported by the belt courses 56 and 57 alone. Normally, the wieners are advanced

20 onto the article conveyor 13 by the input conveyor 15 in the manner indicated in dot-dash lines in FIGS. 1 and 2. However, if desired, wieners can be diverted downwardly between the belt courses 56 and 57. As shown in FIGS. 3 and 4A, a slot 64 is provided in the main frame plate

25 22 through which the wieners can be diverted downwardly. A diverter arm 66 is mounted on a shaft 67. The shaft 67 is pivotally mounted in a frame arm 68 attached to the main frame plate 22 and in similar frame arms 68a mounted on the other input conveyors, as shown

30 in FIG. 2. A handle 69 mounted on the shaft 67 can be swung from the position shown in full lines at which the diverter arm diverts the wieners 14a (FIG. 4) downwardly to the position shown in double dot-dash lines at which the diverter arm is raised above the path of

35 the wieners and the wieners progress along the input conveyor belt courses to the article conveyor 13. A tension spring 71, linking a lug 72 on the handle with a lug 73 mounted on a frame arm 74 holds the handle 69 and diverter arm 66 in selected positions. Stop pins 74

35 and 75 mounted in the frame arm 68 limit swinging of the handle.

Article conveyors

40 As already indicated, the article conveyor 13 is supported on the main housing 10 and on the frame housing 12 (FIG. 1). In FIG. 4 is shown in detail the article conveyor frame 38. The article conveyor frame 38

45 is of generally C-shape and includes a base arm 75b, an upstanding main plate portion 75c, a horizontal upper arm 75d and a depending flange 75e. Frame support

50 brackets 75f are mounted on the base arm 75b and rest on and are attached to cross frame elements, one of which is shown at 75h. The upper face of the horizontal upper arm 75d carries spaced nylon strips 75g adhesively attached thereto on which article buckets 76 can be supported.

55 The article conveyor 13, as shown in FIGS. 5 and 7, includes a plurality of article buckets 76. Each bucket 76 includes a base plate portion 77 (FIG. 8), an upright flange 78 (FIGS. 5 and 7) and downwardly extending flanges 79 and 80 (FIG. 4.). The buckets are connected together with conveyor chains 81 and 82. Flanges 79 and 80 of each article bucket are pivotally attached to upstanding portions 83 (FIG. 7) of links of the conveyor chains.

60 As shown in FIG. 4, the chains run on outer sides of flange 75e and the main plate portion 75c of the article conveyor frame 38 and the chains are guided thereby.

65 As the wieners 14 are delivered from the input conveyors 15 to the article conveyor 13, as indicated most clearly in FIG. 4, the wieners fall onto the buckets of the article conveyor. Ordinarily, each wiener 14 falls into one of the buckets 76 so that a single layer of wieners is disposed on the article conveyor, and the article conveyor is driven (by mechanism to be described hereinafter) at such a speed that, even if all the input conveyors 15 are operating at full capacity, some of the buckets 76 of the article conveyor remain empty. On occasion, more than one wiener may be directed into a single bucket in the manner that the wiener 14b is shown in FIGS. 4 and 5. A plurality of wiper plates 84 are mounted

above the article conveyor for wiping or moving any such improperly positioned wiener into an unoccupied article bucket. Each wiper plate is integrally mounted on a sleeve 85. Each sleeve 85 is pivotally mounted on a horizontal shaft 86. The shafts 86 are mounted on a bracket 87 which, in turn, is attached to the article conveyor frame 38. A stop pin 88 extending into the lower side of the shaft 86 limits swinging of the wiper plate 84 in a counter-clockwise direction (as shown in FIG. 5). However, the plate is free to swing upwardly in a clockwise direction when engaged by an improperly positioned wiener. Centering pins 89 mounted in the shaft 86 are engageable with opposite sides of the sleeve 85 to keep the wiper plate in position on the shaft. When the improperly positioned wiener 14b (FIG. 5) is engaged by the wiper plate 84, the wiener is held back while the wieners 14 pass to the left, as shown in FIG. 5, and the improperly positioned wiener rolls into an unoccupied bucket.

Ordinarily each input conveyor 15 will drop or position each wiener properly in a central position in one of the input buckets as shown at 14c in FIG. 3. On occasion, a wiener will fall into an improperly centered position. Shaker bars 91 and 92 mounted along sides of the article conveyor, serve to properly center the wieners in the article conveyor. The shaker bars 91 and 92 are mounted in U-shaped shaker frames 93, one of which is shown in detail in FIGS. 4 and 5. The shaker frame 93 is supported on a U-shaped pivot frame 94 (FIG. 5) attached to the base arm 75b of the article conveyor frame 38. A bearing sleeve 96 is attached to the base of the shaker frame 93. A pivot pin 97 mounted in the pivot frame 94 and received in the bearing sleeve 96 pivotally supports the shaker frame 93. A cam 98, mounted on the shaker drive shaft 45c, engages a cam follower 99 mounted on a pin 100 supported by arms 100a which are attached to the shaker frame 93 to cause the shaker frame to oscillate as the shaker drive shaft 45c turns. A tension spring 101 holds shaker frame 93 in position for the cam follower 99 to engage the cam 98 so that rotation of the shaker drive shaft 45c causes back and forth oscillation of the shaker frame 93 and the shaker bars 91 and 92 between the position shown in full lines in FIG. 4 and the position shown in dot-dash lines to move wieners to a central position on the article conveyor.

The article conveyor 13 carries the wieners to the left as indicated in FIGS. 1 and 2 to deliver the wieners to the belt conveyor 16 with no more than a single wiener 14 in each article bucket 76, as shown in FIG. 7. As the article conveyor approaches the belt conveyor 16, the chains 81 and 82 pass over a sprocket 102 and a sprocket 102a (FIG. 9), respectively, mounted on a shaft 103. The shaft 103, in turn, is driven by a sprocket 104 mounted thereon. The drive connections to the sprocket 104 are shown in FIGS. 9 and 10. A main drive motor 106 carries a pulley 107 which drives a belt 108. The belt 108 drives a pulley 109 mounted on a shaft 111. A small sprocket 112 mounted on the shaft 111 drives a chain 113 which drives a large sprocket 114 mounted on a shaft 116. The shaft 116 carries a small sprocket 117 which drives a chain 118. The chain 118 in turn, drives the large sprocket 104 mounted on the shaft 103 to drive the article conveyor.

Belt conveyor

As the article buckets swing around the sprockets 102 and 102a, as shown in FIG. 7, each bucket passes very close to lower belts 121 and 121a (FIG. 12) of the belt conveyor 16, and each wiener passes from the article conveyor to the belt conveyor 16. The belt conveyor 16 includes the lower belts 121 and 121a and a pair of spaced upper belts 122 and 123. The belts run on a plurality of rollers which extend cantilever-fashion from a gear housing 124 (FIGS. 7, 11, and 12). The lower belts run

on a drive roller 126 and idle rollers 127, 128 and 129. The drive roller 126 is mounted on a shaft 131 which extends into the gear housing 124 as shown in FIG. 13. The idle rollers 127, 128, and 129 are mounted on stationary shafts 132, 133, and 134, respectively, which are mounted on a wall 136 of the gear housing 124. On the shaft 133 are mounted pivot links 137 and 138 which support a shaft 139 on which an idler roller 141 is rotatably mounted. The roller 141 weights the lower courses of the belts 121 and 121a to maintain tension in the upper courses 122 and 123 thereof so that the upper courses are urged to taut condition. The idle roller 192 carries a knurled sleeve 143a which is attached thereto to turn therewith as the idle roller 192 is turned by the lower belts 121 and 121a.

The drive for the shaft 131 is shown in FIGS. 9, 10 and 16. A sprocket 143a (FIGS. 9 and 10) mounted on the shaft 116 drives a chain 143b. The chain 143b runs on a sprocket 143c mounted on the shaft 131. Since the shaft 116 also is in the drive for the article conveyor, as already explained, the belt conveyor drive shaft and the article conveyor are driven in unison.

The upper belts 122 and 123 (FIG. 12) run on a driven roller 144 and idle rollers 146, 147 and 148. The driven roller 144 is mounted on a shaft 149 which extends into the gear housing 124 and carries a gear 151 (FIG. 13). The shaft 149 also extends through a wall 152 of the gear housing 122 (FIG. 16) and carries a sprocket 153. The sprocket 153 carries a chain 154 which extends around a sprocket 155 and over a sprocket 156. The sprocket 156 is freely rotatable on a shaft 157. The sprocket 155 is mounted on a shaft 157a. The shaft 157a carries gear 157b (FIG. 13) which meshes with a gear 157c mounted on the shaft 131. A pinion 158 (FIG. 16) is mounted on the shaft 157 and is driven by a gear 159 mounted on the shaft 131. As shown in FIG. 12, the idle rollers on 146 and 147 are mounted on stationary shafts 161 and 162, respectively, which are mounted on the wall 136 of the gear housing 124. The drive roller 144 is driven at the same rate as the drive roller 126 but in the opposite direction so that the upper and lower belts of the belt conveyor 16 move at the same speed but the upper belts 122 and 123 move clockwise as shown in FIG. 12 while the belts 121 and 121a move counter-clockwise. Thus, the belts can cooperate to grip wieners therebetween and advance the wieners to the left as indicated in FIGS. 7, 11 and 12. As already pointed out, the belts of the belt conveyor 16 advance in timed relation with the article conveyor. However, the belts of the belt conveyor 16 move at a faster rate so that, as the wieners are advanced by the belt conveyor 16, the wieners are substantially spaced, as shown in FIG. 11, at 14e and 14d.

An idle roller 165 is mounted on a swinging shaft 166 as shown in FIG. 12, and rests on top of the upper belts 122 and 123. The shaft 166 of the idle roller 165 is carried by pivot links 167 and 167a. The pivot links 167 and 167a are pivotally mounted on a stationary shaft 168. The shaft 168, in turn, is mounted on the wall 136 of the gear housing 124. The idle roller 165 weights the upper courses of the belts 122 and 123 so that lower courses 168a of the belts 122 and 123 (only one of which is shown) are urged to taut condition.

The idle roller 148 is mounted on a shaft 169. As shown in FIG. 13, the shaft 169 extends through the wall 136 of the gear housing 124 and is pivotally mounted thereon in bearings, one of which is indicated at 170. The belts 122 and 123 extend around the idle roller 171 which, as shown in FIGS. 11 and 12, is mounted on links 172 and 173. The links 172 and 173 are mounted on the shaft 169. As shown in FIG. 13, the shaft 169 also carries an actuator arm 174 mounted inside the housing. The actuator arm 174 carries a cam follower 176 (FIG. 13) in engagement with a twin-headed cam 177 (FIGS. 13 and 15). The shaft 169 is urged in a clockwise direc-

tion to keep its cam follower in engagement with the cam 177 (FIG. 15) by a compression spring 177a (FIGS. 12 and 15). The compression spring 177a engages a crank arm 177b mounted on the shaft 169. The spring 177a is backed up by an adjustment screw 177c threaded in a boss 177d mounted on the wall 136 of the gear housing 124, as shown in FIG. 12. A lock nut 177e can be threaded thereon to lock the screw 177c in position, as shown in FIG. 15. An adjustment screw 177f mounted on the crank arm 177b engages a stop plate 177g attached to the wall 136 to limit swinging of the shaft 169 in a clockwise direction under the influence of the compression spring 177a. The cam 177 is mounted on a shaft 178 which carries a gear 179. The gear 179 is driven by a gear 181 (FIG. 15) mounted on a shaft 182. The shaft 182 also carries the gear 157b which meshes with the gear 157c mounted on the shaft 131. The cam 177 is turned at such a speed that it makes a half turn for each article conveyor bucket 76, and the idle roller 171 is swung from the full line position of FIGS. 7 and 11 to the dot-dash line position of FIGS. 7 and 11 as each article bucket 76 passes the upper belts of the belt conveyor 16 so that, as article bucket 76 passes, the wiener thereon can swing past the upper belts 122 and 123 but thereafter, as the article bucket moves further downwardly the wiener thereon swings into the space between the belts and is picked up by the belts as the upper belts 122 and 123 in the sections thereof carried by the roller 171 swing back to the full line position of FIGS. 7 and 11 at which the wiener is gripped between courses 142, 143 and 168a of the belts of the belt conveyor 16 and moves into the space between the belts in which these courses are parallel and sufficiently spaced to grip the wieners firmly.

As the wieners 14 advance along the belts, the wieners pass a switch actuator 183 (FIGS. 7, 11 and 12). The switch actuator 183 is mounted on a sleeve 184 pivotally mounted on the shaft 168, as shown most clearly in FIG. 12. The switch actuator 183 is of generally U-shape, and may be formed of spring metal or the like. As shown in FIG. 7, the actuator includes an upper arm 186 and a lower arm 187. As shown in FIG. 8, the switch actuator is mounted between upper belts 122 and 123. A head 188 (FIG. 7) on the lower arm 187 thereof extends downwardly into the path of the wieners 14 traveling between the parallel courses of the belts. As each wiener passes between the belts and engages the head 188 of the switch actuator, the actuator swings from the FIG. 7 position to the FIG. 11 position to actuate a push button switch 189. The switch 189 operates counting mechanism to be described hereinafter.

Reversible diverter roller

When each wiener has passed the switch actuator 183 it passes between the idle rollers 127 and 146 to an area where the belts of the belt conveyor 16 have diverging sections 191 and 192 (FIG. 7). A movable and reversible diverter roller 193 is mounted on a hollow shaft 194 (FIG. 13) which extends through a slot 196 (FIG. 11) in the wall 136 of the gear housing 124. The shaft 194 is rotatably mounted in a sleeve 197 (FIGS. 13 and 14). The sleeve 197 is supported on an arm 198 of a bell crank 199. The bell crank 199 is pivotally mounted on a shaft 201 mounted inside the gear housing 124. A solenoid 202 mounted inside the gear housing on a frame plate 202a has a plunger 202b which engages an arm 202c of the bell crank 199 to urge the bell crank 199 in a counter-clockwise direction as indicated in FIG. 14. A compression spring 203 engages the arm 202c of the bell crank 199 to urge the bell crank clockwise when the solenoid is released. The compression spring 203 is backed up by a stationary bar 206 mounted on the gear housing 124. Ends of the compression spring are received in wells 208 and 209, respectively, in the crank arm 202c and the stationary bar 206, respectively.

A nylon pinion 210 is mounted on the reversible shaft 194 between sections 197a and 197b of the sleeve bearing 197. The pinion 210 is alternately driven by gears 181 and 211. As indicated by arrows in FIGS. 13 and 14, the gear 211 is driven counter-clockwise and the gear 181 is driven clockwise. The drive for the gear 181 has already been described. The gear 211 is mounted on a shaft 211a which carries a gear 211b. The shaft 211a is driven by the gear 151. Thus, when the diverter roller 193 is in its upper position, as shown in full lines in FIGS. 7 and 11, the diverter roller 193 is driven clockwise and, when the reversible roller is in its lower or dot-dash line position, as shown in these views, the diverter roller is driven in a counter-clockwise direction.

Article receiving trays

From the diverter roller 193, the wiener passes into a tray unit 211c. The tray unit 211c includes trays 212 and 213 (FIGS. 7 and 7A) and a cover 214. The lower tray 212 includes an angle-shaped body having a main plate portion 214a and a back flange 214b mounted on pivot legs 214c and 214d (FIG. 17C). The pivot legs are mounted on a pivot shaft 215 (FIGS. 7 and 7A) carried by brackets 216 and 217, which are mounted on the top of the main housing 10. When in the operative position shown in full lines in FIG. 7, the main plate portion 214a thereof rests on a post 219 (FIG. 7A) mounted on the housing. The upper tray 213 includes an angle-shaped body having a main plate portion 213a and a back flange 213b mounted on pivot lugs 221 and 222 (FIG. 17C). The pivot lugs 221 and 222 are pivotally mounted on the shaft 215. When the upper tray is in operating position, as shown in full lines in FIG. 7, the pivot lugs 221 and 222 engage the upstanding back flange 214b of the lower tray 212 (see FIG. 7A). The cover plate 214 is provided with a pivot leg 226 (FIG. 17C), which is also pivotally mounted on the shaft 215. When the cover plate 214 is in its operating position, the pivot leg 226 thereof engages the pivot lugs 221 and 222 of the upper tray to hold the cover in proper position. When desired, the cover and trays can be swung back to the position shown in FIG. 7A for ready access. When the machine is in operation, the trays and cover plate are in position shown in FIG. 7, so that the wieners leaving the belt conveyor 16 are diverted into the trays. When the reversible roller 193 is in its upper (full line) position of FIG. 7, the wieners are diverted into the lower tray 212. When the reversible roller 193 is in its lower (dot-dash line) position of FIG. 7, the wieners are diverted into the upper tray 213. An end portion 227 of the main plate portion 213a of the upper tray adjacent the belt conveyor 16 is enlarged and is disposed in closely spaced relation to upper and lower high speed rollers 228 and 229. The rollers 228 and 229 are mounted on a shaft 231 and on the shaft 157, respectively (see FIG. 16). As already pointed out, the shaft 157 carries the pinion 158 and is driven thereby. As shown in FIG. 16, gears 233 and 234 on the shafts 231 and 157 mesh to drive the shafts 231 and 157 and the rollers 228 and 229 in opposite directions and at equal speeds. The upper high speed roller 228 rotates counter-clockwise and the lower high speed roller 229 rotates clockwise as indicated by arrows in FIG. 7. When the diverter roller 193 is in its upper position as shown in FIG. 7 is full lines, wieners pass between the diverter roller 193 and the diverging section 191 of the lower conveyor belts and the diverging roller 193 is sufficiently spaced from the diverging section 191 to grip each wiener as it passes. In this position, the diverging roller rotates clockwise to urge the wiener toward the lower tray. Each wiener after passing below the diverter roller 193, passes below the lower high speed roller 229 and onto the lower tray 212. Similarly, when the diverter roller 193 is in its lower position, as shown in dot-dash lines in FIG. 7, each wiener 75 passes above the diverter roller 193. In this position,

the diverter roller 193 is sufficiently spaced from the diverging section 192 of the upper conveyor belts to grip each wiener as the wiener passes above the diverter roller and the diverter roller 193 rotates counter-clockwise to urge the wiener onto the upper tray 213 with the wiener passing above the high speed roller 228 onto the upper tray 213. When a predetermined number of wieners (5) has been counted into one of the trays, the diverter roller position is shifted in response to the count of wieners by apparatus to be described hereinafter, so that a predetermined number of wieners can be counted into the other tray. As shown in FIG. 7, the main plate portions 214a and 213a of the trays 212 and 213 slope downwardly and to the left so that wieners roll into position supported by the upwardly projecting back flanges 214b and 213b thereof.

Article rams

When a predetermined number of wieners (five) has been counted onto the lower tray 212, one of the wrapper cards 19 (FIGS. 20A and 21) is positioned in a bucket 18a (FIGS. 7 and 20A) at a loading station opposite the rams by apparatus to be described hereinafter. Then a lower article or wiener ram 233a (FIG. 17A) is advanced through space between the plate portion 214a of the lower tray and the plate portion 213a of the upper tray to advance the wieners in the lower tray axially into the wrapper card in the bucket 18a, as indicated in FIG. 21. The lower wiener ram 233a is mounted on a shaft 233b which reciprocates in a bore 233c (FIG. 17) in a bearing block 233d attached to the upper face of the main housing 10. Guide blocks 234 and 236 of nylon or the like mounted on the back of the lower ram can engage the plate portion 214a of lower tray 212 as shown in FIG. 21, to guide the lower ram 231 therethrough. A pin 237 (FIG. 17C) mounted on the bearing block 233 can be received in an opening 237a in the guide block 236 to prevent pivoting of the lower ram when free of the plate portion 214a of the lower tray 212.

When the lower ram 233a has returned to its retracted or normal position as shown in FIG. 20, and the predetermined number of articles (five) has been counted onto the upper tray 213, an upper ram 238 is advanced through the space between the plate portion 213a of the upper tray 213 and the cover plate 214 to advance the wieners on the upper tray axially into the bucket on top of the wieners already in the bucket as shown in FIG. 7. The ram 238 is mounted on a shaft 239 which reciprocates in a bore 241 in the bearing block 233d (FIG. 17). Guide blocks 242 and 243 attached to the ram 238 can engage the plate portion 213a (FIG. 21) of the upper tray 213 to guide the upper ram 238 therethrough. A pin 244 (FIGS. 17C and 17D) mounted on the bearing block 233 is received in a bore 245 (FIG. 17) in the guide block 243 to prevent inadvertent swinging of the upper ram when withdrawn from the upper tray.

The lower ram 233a is driven by cables 246 and 247. One end of the cable 246 is connected to an upper end of a tension spring 248 (FIG. 17). The lower end of the tension spring 248 is attached to a lug 249 attached to a base plate 250 of the main housing 10. The cable 246 extends upwardly from the tension spring 248 over a pulley 251 rotatably mounted on the bearing block 233d. The pulley 251 has two grooves 252 and 253 in the peripheral face thereof. The cable 246 runs in the groove 252 and the cable 247 runs in the other groove 253. The upper end of the cable 246 is attached to a block 254 which, in turn, is mounted upon the shaft 233b of the lower ram. An upper end of the cable 247 is attached to the lower ram 233a. The cable 247 extends over the pulley 251 and the lower or other end of the cable 247 is attached to a pivotally mounted L-shaped actuator arm 256. The arm 256 is pivotally mounted on the pivot shaft 257 rigidly mounted on an

upright wall 258 inside the main housing 10. The actuator 256 includes a circumferentially extending arm 259 which has an outer face 261 extending in a circumferential direction around the pivot axis of the shaft 257. A groove 262 on the face 261 receives the cable 247. A radial arm 263 of the actuator 256 connects the circumferential arm to the pivot. A fastener 264 on the cable attaches the cable to the radial arm 263. A cam follower 266 mounted on the radial arm 263 is engaged by a heart-shaped cam 267 for swinging the actuator 256 and driving the lower ram 233a. The cam 267 is mounted on a shaft 268. A brake drum 269 (FIGS. 17A and 17B) is mounted on the shaft 268. A brake strap 271 engages the drum 269 to keep a continuous drag on the shaft 268 and prevent free running thereof when driving force is released. One end of the brake strap 271 is attached to a bracket 271a mounted on the upright wall 258. The other end of the brake strap 271 carries an angle-shaped end lug 271b. An adjustment bolt 271c attached to the bracket 271a is received in an opening 271d in a flange of the end lug 271b and carries an adjustment nut 271e for adjusting the drag of the brake strap 271. The drive for the shaft 268 is shown in FIGS. 9 and 18. The shaft 268 is driven by a single revolution clutch 272. The clutch 272, in turn, is driven by a sprocket 273 (FIG. 9). The sprocket 273, in turn, is driven by a chain 274 (FIGS. 9 and 10) mounted on a sprocket 275. The sprocket 275 is mounted on the shaft 111, the drive for which has already been set out herein above.

The clutch 272 is operated by a stop arm 277 (FIGS. 18 and 9A). When a solenoid 278 is energized, the solenoid urges the stop arm 277 to swing counter-clockwise upon a pivot 278a as shown in FIG. 9A to release a stop ring 279 of the clutch 272 and permit engagement of the clutch 272 by mechanism thereinside, not shown in detail. When the solenoid 278 is de-energized, the stop arm 277 is urged back in a clockwise direction by a compression spring 280 to engage a stop shoulder 281 on the stop ring 279 to cause disengagement of the clutch when the clutch has made a single revolution. Each time the clutch solenoid 278 is energized and the clutch 272 turns the shaft 268 one revolution, the cam 267 (FIG. 17) makes a single revolution to drive the lower ram 233a through a single cycle from its normal position to move crosswise of the lower tray and return to its normal position.

The upper ram 238 is driven by a drive which includes cables 283 and 284 (FIG. 17) a pulley 286 having grooves 287 and 288, an L-shaped mounted actuator 289 pivotally mounted on a shaft 290 mounted on the wall 258, a cam follower 291 and a heart-shaped cam 292 mounted on a shaft 293, all of which are similar in construction and operation to parts of the drive for the lower ram already described. The drive to the shaft 293 includes an electro-magnetic clutch 294 (FIG. 9) driven by the shaft 111. A shaft 296 driven by the electro-magnetic clutch 294 carries a sprocket 297. The sprocket 297 drives a chain 298. The chain 298 drives a sprocket 299 which is mounted on a jack shaft 301. A sprocket 302 mounted on the jack shaft 301 (FIG. 9) drives a chain 303 (FIGS. 9 and 10). The chain 303 drives a sprocket 304 (FIG. 9) mounted on the shaft 293. As shown in FIGS. 9, 10, and 20 a Geneva gear driving plate 305 is mounted on the shaft 293 and is driven thereby. A switch actuator block 306 is mounted on one side of the sprocket 304 as shown most clearly in FIG. 20. A limit switch 307 is actuated thereby. When an electric signal is delivered to the electro-magnetic clutch 294 upon counting of the predetermined number (five) wieners into the upper tray, the clutch 294 is energized to provide a driving connection for driving the shaft 293. When one complete turn has been made by the shaft 293, the switch actuator block 306 engages a roller 308 on an actuator arm 309 of the switch 307 to cause an electric

signal to the electro-magnetic (FIG. 9) clutch 294 causing release thereof through operation of an electrical circuit to be described hereinafter. Each time five wieners are counted into the upper tray the shaft 293 makes one complete revolution to cause the upper ram to move from its normal positions as shown in FIG. 20A through the upper tray and return to its normal position.

Details of construction of the electro-magnetic clutch 294 are shown in FIG. 27. Drive connections already described drive the input shaft 111 thereof. The shaft 111 drives an armature 310 which rotates continuously while the machine is in operation. Energization of a coil 311 causes gripping of plates carried by the armature with plates carried by a spider 312. The spider is mounted on the output shaft 296. When the magnet coil 311 is de-energized, a magnet coil 313 is energized to cause plates 314 of the spider to engage plates 315. The plates 315 are mounted on a stationary drum 316 attached to the clutch frame work and act as a brake to stop rotation of the output shaft 296 when the magnet coil 313 is energized and the actuating coil 311 is de-energized.

Card feeding apparatus

The wieners are wrapped in cards 19, one of which is shown in detail in FIG. 26. The wrapper card 19 includes a base portion 19a which underlies the wieners packed therein, side panels 19b and 19c and end flaps 19d and 19e. Fastener elements 317 and 318 at the ends of the end flaps 19d and 19e, respectively, can be engaged, as shown in FIG. 30 to close a package. Lines of weakening indicated in dot-dash lines at 319, 319a, 319b, and 319c permit ready folding of the card 19 about wieners 14 as shown in FIG. 7.

In addition a rectangular flat card 320 can be packaged inside each wrapper card 19, as indicated in FIG. 30. Each rectangular card 320 is rectangular shape and of dimensions which are somewhat smaller than the dimensions of the base portion 19a of the wrapper card (FIG. 26).

The wrapper cards 19 and rectangular cards 320 are mounted in the card holder 21 (FIGS. 18, 22, and 24) with the wrapper cards 19 in flat position as shown in FIG. 24. The card holder 21 includes spaced frame plate 321 and 322 (FIG. 22). The frame plates are mounted on the main housing 10 as shown in FIGS. 1 and 18. Inner edges of the frame plates 321 and 322 are spanned by card stripping plates 323 and 324 (FIG. 22). The card stripping plate 323 is provided with a circular opening 326 for receiving a vacuum cup 327 (FIG. 24), and the card stripping plate 324 is provided with a circular opening 328 for receiving a vacuum cup 329 (FIG. 24). On the frame plates 321 and 322, are mounted upper flange tracks 331 and 331a and lower tracks 332 and 332', respectively. The wrapper cards 19 are mounted on the upper tracks 331 and 331a as shown in FIG. 24. Shoulders 332a (FIG. 26) of the wrapper cards 19 rest on the tracks. The rectangular cards 320 are mounted on the lower tracks 332 and 332' as shown in FIG. 24. The tracks slope downwardly and to the left as shown in FIGS. 22 and 24. A weight 333 running on the tracks 332 and 332a behind the rectangular cards 320 urges the rectangular cards to the left as shown in FIG. 24. A similar weight 334 running on weight guide flanges 335 parallel to and below the upper tracks 331 and 331a urges the wrapper cards 19 to the left as shown in FIGS. 22 and 24.

The lowermost of the wrapper cards 19 in the card holder 21 (FIG. 24) is held in place at the bottom of the upper flange tracks 331 and 331a by lower stop members 336 (only one of which is shown, FIGS. 22 and 24) and upper stop members 337. The upper stop members are mounted on the frame plates 321 and 322. Similarly, the rectangular cards 320 are held by lower stops 338, only one of which is shown, mounted on

the lower tracks 332 and 332' and by an upper stop 339 mounted on an inverted channel shaped bridge frame 341 which spans the frame members 321 and 322.

The vacuum cups 327 and 329 are carried by an upright frame bar 342. The frame bar 342 and the vacuum cups 327 and 329 can move toward the wrapper cards 19 and rectangular cards 320 to the position shown in FIG. 24 in dot-dash lines at which the vacuum cup 327 engages the lowermost wrapper card 19' and the vacuum cup 329 engages the lowermost rectangular card 320'. When the vacuum cups are in this position a vacuum is impressed on the vacuum cups by valving apparatus to be described hereinafter so that the vacuum cups grip the lowermost cards. Then the vacuum cups can be withdrawn to the position shown in full lines in FIG. 24. When the vacuum cups are in this position the vacuum thereof is released by the valving apparatus, and, as the vacuum cups are further withdrawn to the double dot-dash line position, the cards are stripped from the vacuum cups by the stripping plates 323 and 324 and are freed to fall to the position shown in FIG. 24 in which the cards 19'' and 320'' are shown in double dot-dash lines. Sloping guides 343 (FIG. 22) and 344 (FIG. 24) mounted on the frame plates guide the cards to this position. The cards 19'' and 320'' are also shown in this position in FIGS. 23 and 25. In this position, the shoulders 332a (FIG. 26) of the wrapper card 19'' are received on nylon stop blocks 345 (only one of which is shown in FIGS. 22, 23, and 25) mounted on support brackets 346 attached to the frame plates 321 and 322. A flange 346a of generally channel-shaped upright card guide frame 346 backs up the wrapper card 19'' when in this position. The rectangular card 320'' is supported on nylon blocks 346c, each of which is mounted between the flange 346a and a back flange 346d of one of the card guide frames 346b on one of the support brackets 346. Only one set of card supporting members has been shown, namely that supported by the frame plate 321, and it is to be understood that similar card supporting members are mounted on the frame plate 322.

A vacuum for the vacuum cups 327 and 329 is supplied through a vacuum line 349 (FIG. 18). The vacuum is supplied by a vacuum pump 351 (FIG. 10), not shown in detail, and driven by a motor 352. The vacuum line 349 is connected to the vacuum pump 351 by connecting tubes, not shown. An upper end of the vacuum line 349 is connected to a metal tube 353 brazed to an extension arm 354 integral with the frame member 321. The tube 353 communicates with an opening 355 (FIG. 19D) in the frame arm 354. As shown in FIGS. 22 and 24, horizontal angle-shaped guides 356 and 357 are mounted on the arm 354. A nylon plate spacer member 357a (FIG. 19C) is mounted between the guide 356 and the frame arm 354. A similar nylon spacer member 358 is mounted between the guide 357 and the frame arm 354. On flange arm 359 of an angle-shaped slide member 360 is mounted in the guides 357 and 358 for sliding therein with a face 360a thereof (FIG. 19D) in engagement with the nylon spacer members. The frame bar 342, on which the vacuum cups 327 and 329 are carried, is mounted on the other flange 361 of the slide member 360. A copper pipe 363 is brazed to the slide arm 362 and is in communication with the vacuum cups through lines 364 (FIGS. 18 and 24). The pipe 363 also communicates with an opening 366 in the slide arm 357. A groove 368 is formed in the face 360a of the slide arm 359 in communication with the opening 366 and the pipe 363. When the slide arm 359 is at the position shown in FIG. 19D in full lines, the vacuum line 349 (FIG. 18) and the pipe 353 are in communication through the slot 368 with the pipe 363 so that the vacuum cups 327 and 329 are connected to vacuum. However, when slide arm 359 moves to the position shown in dot-dash lines in FIG. 19D the groove 368 is in communication with a vent hole 371 in the frame arm 354 to release the vacuum.

The drive for moving the slide member 360 is shown in FIGS. 18 and 20A and associated views. A lug 372 mounted on the slide member 360 extends through a slot 373 (FIGS. 18 and 19A) in the frame arm 354. One end of a cable 374 (FIG. 18) is attached to the lug 372. In addition, a spring clip 376 is mounted on the lug 372. One end of a tension spring 377 is attached to the spring clip 376. The other end of the spring 377 is attached to a stationary lug 378 mounted on the frame plate 321. The cable 374 passes over pulleys 378a and 378b mounted on shafts 378c and 378d respectively. The shafts 378c and 378d are mounted on the frame plate 321. The lower end of the cable 374 is attached to a crank arm 379. The crank arm 379 is mounted on a shaft 381 which is rotatably mounted in bearing sleeves 382 and 383 (FIG. 19) mounted on the frame wall 321. As shown in FIG. 22, a wrapper folding member 384 is also mounted on the shaft 381. A pivot pin 385 is mounted on the wrapper folding member 384 radially spaced from the shaft 381. An upper end of an actuator rod 386 is pivotally mounted on the pivot pin 385 so that, when the actuator rod 386 moves up and down, the wrapper folding member swings between the raised position shown in FIG. 19 and a lowered position shown in FIG. 22 and in full lines in FIG. 23. As shown in FIG. 18 the lower end of the actuator rod 386 is pivotally attached to a crank arm 387. A tension spring 388 links a lug 389 on the actuator rod 386 and a stationary anchor 391 to urge the actuator rod downwardly. The crank arm 387 is mounted on a shaft 392. The shaft 392 is pivotally mounted in brackets 393, only one of which is shown. A second crank arm 394 is mounted on the shaft 392. The second crank arm 394 carries a cam follower 396 (FIG. 9A) which engages a cam 397 mounted on the shaft 268. As already pointed out, the shaft 268 makes one revolution each time five wieners are counted into the lower tray, and one wrapper card and one rectangular card are delivered each time five wieners are counted into the lower tray.

At the same time as the vacuum cups make their cycle, the wrapper folding member 384 swings from its raised position (FIG. 23, triple dot-dash line position) to the lowered full line position (FIG. 23) and back to its retracted (triple dot-dash line) position. As the wrapper folding member starts to swing it engages the rectangular card 320" and the wrapper card 19" supported on the stop blocks 345 and 346c and urges the cards to the left as shown in FIGS. 23 and 24. As the wrapper folding member starts to swing, the upper portion of the wrapper card engages an upper frame guide 398 mounted on a channel shaped bracket 399 (FIG. 22) which spans the frame members 321 and 322. The manner in which the upper portion of the wrapper card is folded as it passes the upper frame guide 398 is indicated in full lines in FIG. 24 where the wrapper card 19 is shown folding at score line 319a. In addition, as the wrapper folding member swings to the position shown in double dot-dash lines in FIG. 23, the lower portion of the wrapper card engages a lower guide frame 402 to fold the wrapper card at the score line 319b. As the wrapper folding member continues to swing downwardly as shown in FIG. 23 to the full line position, the wrapper card is further folded to the position shown in full lines where the wrapper card is folded between the guide frame 402 and a guide frame 404 to the full line position of FIG. 23 with the rectangular card 320 inside the wrapper card 19. The swing of the card folding member is so timed that, while the wrapper folder is swinging in card folding direction, the vacuum cups are moving in a direction to engage the next card.

The wrapper folding member dwells in its lower position for a sufficient time to permit the cards to be advanced into one of the package buckets 18. The construction of a card ram 403 for moving the card is shown most clearly in FIGS. 19 and 23. The card ram 403 includes a main block 407 having lengthwise guide slots 408 and 409 in side faces thereof. The slots 408 and

409 receive guide tracks 411 and 413 respectively. The guide tracks are mounted on the main housing 10 on opposite sides of a slot 413 (FIG. 23) therein. Z-shaped support frames 414 and 416 underlie the tracks 411 and 412 respectively and are mounted on the main housing 10. A slot 417 is formed in a rear end of the main block 407. A transverse pin 418 is mounted in the slot 417 and is engaged in bifurcations 419-421 at an upper end of an actuator crank 422 (FIGS. 18 and 20A). The actuator crank 422 swings between the full line and the dot-dash line positions of FIG. 20A to advance the card ram between the FIG. 19 position and the FIG. 20 full line position. As shown in FIG. 23, the main block of the card ram extends above the tracks 411 and 412 while the card folding member holds the wrapper card 19 and the rectangular card 320 close to the tracks. When the card ram moves from the position shown in dot-dash lines in FIG. 20a to the full position, the cards are advanced and moved by the card ram from the dot-dash line position to the full line position at which the cards are received in the bucket 18a. A U-shaped card retainer 423 of spring metal is attached to the top of the main block 407 (see FIG. 19). Fingers 424 and 425 of the card retainer 423 ride up on nylon blocks 425a and 425b when the card ram 403 is retracted. When the card ram 403 starts to advance, the fingers 424 and 425 engage the cards to hold the cards down on the tracks as shown in FIG. 23 so that the cards are held in position to be engaged by the main block 407 of the card ram 403. When the cards reach the full line position of FIG. 20A the cards drop into the bucket 18a under downward urging of the spring fingers 424 and 425 and pass over shoulder flanges 426 at inner ends of the tracks which prevent retraction of the cards upon retraction of the card ram 403. As shown in FIGS. 19 and 20A, a wiener stop plate 427, mounted on the frame plate 321 (see FIG. 22) hangs down over the tracks 411 and 412. The stop plate 427 is in position to be engaged by wieners leaving the trays when ejected by the wiener rams so that the wieners are positioned in the bucket 18a, and centered on the cards (see FIG. 20A).

The drive for the card ram is shown in FIGS. 18 and 20A. The crank 422 is pivotally mounted on a frame flange 428 on a pivot 428a. An adjustable link 429 connects pivots 431 and 432 on the crank 422 and on a crank 433 respectively so that the crank 422 and crank 433 swing together. The crank 433 is mounted on a sleeve 434 (FIG. 18) pivotally mounted on a shaft 436. The shaft 436, in turn, is mounted in the frame flange 428 and an adjacent frame 437. A second crank arm 438 mounted on the sleeve 434 carries a cam follower 439. The cam follower 439 runs on a barrel cam 441 mounted on the shaft 268. A tension spring 441a links a clip 441b mounted on the pivot 432 with a stationary lug 441c to hold the cam follower 439 in engagement with the barrel cam 441. Thus, for each revolution of the shaft 268, the card ram 403 makes one cycle from the dot-dash line position of FIG. 20A to the full line position and return.

Package conveyors

Details of construction of the buckets 18 of the package feeding conveyor 17 are shown in FIGS. 7, 8, and 20A. Each package bucket 18 includes an angle-shaped main section 442 (FIG. 7) and a pivotally mounted front section 443. The package buckets are mounted on a drive chain 444. Links of the drive chain 444 are provided with upstanding lugs 446. A bracket 447 attached to the lower side of the main section 442 is mounted on two spaced upstanding lugs 446a and 446b. The pivotally mounted front section 443 is mounted on the lug 446b. The front section can swing between the position shown at 443 and the position shown at 443a. A leaf spring 448 attached to the bottom of the main section 442 urges the pivotally mounted front section to the closed

position shown at 443. When the package bucket reaches the loading station opposite the wiener trays and rams where the package bucket 18a is located, an actuator arm 449 of the pivotally mounted front section 443 engages a roller 451 (FIG. 20A) in the manner that the actuator arm 449a is shown to swing the pivotally mounted section open so that, when the cards and wieners are being pushed into the bucket, the bucket is open. When the bucket is in this position (see FIG. 7), a lower plate portion 442a of the main section 442 is parallel to and opposite the lower tray 212 but below the lower tray 212. When a bucket has been filled, the bucket is moved to the position where the bucket 18b is shown, and pivotally mounted front section 443b closes to fold the wrapper card 19 further around the wieners. As the bucket 18 advances along the machine, the package can be inspected and the end flaps 19d and 19e (FIG. 26) can be closed as indicated in bucket 18c. Finally, the bucket and chain pass over an idle sprocket 452 to a position where a bucket 18d is shown and where the actuator arm 449d engages a block 453 to again open the pivotally mounted front section, whereupon the finished package is discharged. The package 453a is discharged onto a sloping face 454 of a package conveyor housing 455 and slides downwardly as indicated at 455a while the buckets are received in an opening 456 (FIG. 8) in the sloping face. While traveling along the machine, the buckets advance with the lower plate portion 442a resting on nylon strips 456a (FIG. 8) supported on housing flanges 456b and 456c (FIG. 20A).

The drive for the package conveyor 17 includes a drive sprocket 456 (FIG. 7) mounted on a shaft 457 and on which the drive chain 44 runs. As shown in FIG. 20, the shaft 457 carries a Geneva gear 458 which is engageable by a drive lug 459 mounted on the Geneva gear driver 305. Each time the Geneva gear driver 305 makes a revolution upon energization of the electro-magnetic clutch 294, the Geneva gear 458 and drive sprocket 456 make a quarter turn to advance the buckets one station along the machine.

Electrical circuit

The electrical connections of the machine are illustrated schematically in FIG. 28. In FIG. 28, power leads are indicated at 460 and 461. The power lead 461 can be connected to ground. Each article such as a wiener causes the switch 189 to close and then re-open. When the contacts of the switch 189 close, a solenoid 463 draws an actuator arm 463a to the right as shown in FIG. 28. Upon opening of the contacts of the switch 189, a spring 463b draws the actuator arm 463a to the left as shown in FIG. 28 to advance a ratchet 463c one notch. The ratchet 463c carries a cam 464. The cam operates a switch 465. One contact of the switch 465 is connected to the power lead 460. The other contact of the switch 465 is connected through a lead 466 to one side of a coil 467 of a first control relay 468. The other side of the coil 467 is connected to ground. The cam 464 is so constructed that the coil 467 is de-energized while the first five articles are counted and, thereafter is energized while the succeeding five articles are counted through a circuit from the power lead 460 through a lead 469, the contact arm 465, and the coil 467 to ground.

The first control relay has two sets of contacts 471-472 and 473-474. The contacts 471-472 are normally closed, and contacts 473-474 are normally open. When the normally open contacts 473-474 are closed upon energizing of the coil 467, a solenoid coil 202 is energized, and the bell crank 199 for the reversible roller 197 is at a position to divert articles into the upper tray. When the normally open contacts 473-474 are open, the solenoid coil 202 is de-energized and the reversible roller 193 is at a position to divert articles into the lower tray.

As the normally closed contacts 471-472 close, a coil 479 of a second control relay 481 is energized by a cir-

cuit from the power lead 460 through a lead 482, the normally closed contacts 471-472 of the first control relay 468, a lead 483, contacts of a normally closed time-delay relay 484, contacts of a normally closed time-delay relay 486, and a lead 487, and the coil 479 to ground. When the second control relay 481 is energized, normally closed contacts 488-489 thereof are opened. The normally closed contacts 488-489 supply energy to the brake solenoid 313 of the electro-magnetic clutch 294 and, upon opening of the normally closed contacts 488-489, the brake solenoid 313 is de-energized to release the brake. At the same time, normally open contacts 491-492 of the second control relay 481 close. The contacts 491-492 control the drive solenoid 311 of the electro-magnetic clutch 294 and, upon closing of the contacts 491-492 the drive solenoid 311 is energized starting rotation of the drive shaft 296 thereof. As the drive shaft 296 starts to turn, the limit switch 307 closes. At the same time as the coil 479 of the second control relay 481 is energized, a coil 493 of the second time delay relay 486 is energized through the lead 483. In addition coil 496 of the time delay relay 484 is energized at the same time. Then, a predetermined time after the coils of the time delay relays 486 and 484 are energized, the time delay relays open. The time is set to be sufficient to permit the drive shaft 296 to make major portion of a turn but not a complete turn. After the time delay relays 484 and 486 open, the coil 479 of the second control relay 481 continues to be energized through a circuit from the power lead 460, through a lead 498, normally open relay contacts 499-501, a lead 502, the contacts of the limit switch 307, a lead 503, normally open contacts 504-506 of the second control relay 481, a lead 507 and the coil 479 to ground. When the driven shaft has completed one revolution, the limit switch 307 is opened by action of the switch actuator block 306 to de-energize the coil 479, of the second control relay, whereupon, the drive solenoid 311 is de-energized by opening of normally open contacts 491-492 and the brake solenoid 313 is energized through normally closed contacts 488-489, so that the rotation of the shaft 296 is stopped. As has already been pointed out that when the drive shaft 296 turns the upper ram moves in a direction to eject articles axially from the upper tray. Then, as the upper ram returns to its normal position, the package conveyor 45 is advanced sufficiently to move a filled bucket one station and replace the filled bucket with an empty bucket.

Meanwhile, the count of articles continues as articles are being diverted into the lower tray, and the cam 464 advances to a position where the relay coil 467 of the first control relay 468 is energized, whereupon the normally closed contacts 471-472 are opened and the normally open contacts 473-474 are closed. Closing of the contacts 473-474 energizes the solenoid coil 202 to swing the diverter roller 193 to a position to divert articles 55 into the upper tray. At the same time, the solenoid 278 is energized through a circuit from the power lead 460 through the contacts 473-474, a lead 509, contacts 511-512 of a normally closed time delay relay 513 and the solenoid coil 278 to ground. Energizing of the solenoid 60 278 withdraws the stop arm 277 from the clutch collar 279 of the single-revolution clutch. In addition, at the same time, solenoid 514 of the time delay relay 513 is energized and, a predetermined time after energizing, the time delay relay opens the switch contacts 512-513.

Opening of these contacts occurs shortly after the clutch has started to make a revolution but before completion of a single revolution. As already pointed out, as the single revolution clutch turns, the card folding arm first swings downwardly to fold one of the wrapper cards. At the same time, the card picking cups move toward the cards to be in position to pick another card therefrom. Then, when the card folder has reached the bottom of its swing, the card ram moves crosswise thereof to advance the card into a bucket. As the card ram approaches its extreme feeding position, the bottom ram starts mov-

ing in a direction to advance articles into the bucket at the loading station.

Operation

The operation of the machine is shown schematically in FIG. 29. At the start of a count of wieners, the diverter roller 193 is moved to its upper position at which wieners are diverted downwardly and the first five wieners are counted into the lower tray. Meanwhile, the upper ram moves out and back pushing wieners from a previous count out of the upper tray and into a bucket at the loading station. As the top ram moves back, the package conveyor starts and indexes the package conveyor one station. At the fifth count, the diverter roller is moved to its lower position at which wieners are directed upwardly and the count of wieners continues with the wieners moving into the upper tray. In addition, at the fifth count, the card picking vacuum cups start to move in, and the card folder swings downwardly so that a wrapper card and a rectangular card are folded into the folded position by the wrapper folding member as the card picking vacuum cups move into engagement with the next card. Then, when the wrapper card has been folded down with the rectangular card thereinside, the card ram moves in a direction to push the cards into a bucket. Just before the cards reach fully advanced position in the bucket, the bottom ram starts moving out so that the wieners in the bottom tray are moved onto the cards. Meanwhile, the card folding member remains in its down position to prevent inadvertent unfolding of the wrapper card. Then the card ram moves back to its retracted position and the card folding member moves back to its retracted position while the card picking vacuum cups move outwardly to the stripping position where the vacuum is broken and the cards fall into position for the next cycle.

Conclusion

The machine quickly and accurately counts wieners at high speed and places the wieners in packages. The machine has been described particularly with reference to an embodiment for use in packaging wieners and the like. However, the machine can readily be adapted for use in packaging other types of cylindrical articles and the like. Moreover, the machine is subject to structural modification without departing from the spirit and scope of the appended claims, and it is not desired to limit the invention except as set forth in the claims.

Having described our invention what is claimed as new and desired to be secured by Letters Patent is:

1. A machine for sequestering groups of articles which comprises a pair of continuous belt conveyors having spaced courses with substantially parallel sections spaced sufficiently to engage the articles therebetween for moving the articles along the belt conveyors, means for counting said articles while traveling between said courses, said courses having diverging discharge sections, a diverter roller extending transversely of and between said diverging sections, means for mounting said diverter roller for movement longitudinally between a first position spaced from one of the courses and adjacent the second of the courses to divert articles adjacent the first course and a second position spaced from the second course and adjacent the first course to divert articles adjacent the second course, means for rotating the diverter roller in a direction to cooperate with the first course when in the first position to divert articles adjacent the diverging section of the first course and in a direction to cooperate with the second course when in the second position to divert articles adjacent the diverging section of the second course, trays adjacent the diverging sections of the courses for receiving predetermined numbers of articles, and means for moving said diverter roller between its positions in response to the count of articles, whereby a predetermined number of articles is counted into each of the trays.

2. A machine for sequestering groups of articles which comprises a pair of continuous belt conveyors having

spaced courses with substantially parallel sections spaced sufficiently to engage the articles therebetween for moving the articles along the belt conveyors, means for counting said articles while traveling between said courses, said

5 courses having diverging discharge sections, a diverter roller extending transversely of and between said diverging sections, means for mounting said diverter roller for movement longitudinally between a first position spaced from one of the courses and adjacent the second of the courses to divert articles adjacent the first course and a second position spaced from the second course and adjacent the first course to divert articles adjacent the second course, means for rotating the diverter roller in a direction to cooperate with the first course when in the first position to divert articles adjacent the diverging section of the first course and in a direction to cooperate with the second course when in the second position to divert articles adjacent the diverging section of the second course, trays adjacent the diverging sections of the courses for receiving predetermined numbers of the articles, means for moving said diverter roller between its positions in response to the count of articles, whereby a predetermined number of articles is counted into each of the trays, and means for alternately receiving articles from one of the trays while articles are directed toward the other of the trays.

3. A machine for sequestering groups of articles which comprises a pair of continuous belt conveyors having spaced courses with substantially parallel sections spaced

30 sufficiently to engage the articles therebetween for moving the articles along the belt conveyors, means for counting the articles, said courses having diverging discharge sections, a diverter roller extending transversely of and between said diverging sections, means for mounting said

35 diverter roller for movement longitudinally between a first position spaced from one of the courses and adjacent the second of the courses to divert articles adjacent the first course and a second position spaced from the second course and adjacent the first course to divert articles adjacent the second course, means for rotating the diverter roller in a direction to cooperate with the first course when in the first position to divert articles adjacent the diverging section of the first course and in a direction to cooperate with the second course when in the second position to divert articles adjacent the diverging section of the second course, trays adjacent the diverging sections of the courses for receiving predetermined numbers of the articles, and means for moving said diverter roller between its positions in response to the count of articles, whereby a predetermined number of articles is counted into each of the trays.

4. A machine for sequestering groups of cylindrical articles of uniform diameter which comprises a pair of continuous belt conveyors having spaced courses with substantially parallel sections spaced sufficiently to engage the articles therebetween for moving the articles longitudinally along the belt conveyors with the articles extending transversely of the belt courses, means for counting said articles while traveling between said courses, said courses having diverging discharge sections, a diverter roller extending transversely of and between said diverging sections, means for mounting said diverter roller for movement longitudinally between a first position spaced from one of the courses and adjacent the second of the courses to divert articles adjacent the first course and a second position spaced from the second course and adjacent the first course to divert articles adjacent the second course, means for rotating the diverter roller in a direction to cooperate with the first course when in the first position to divert articles adjacent the diverging section of the first course and in a direction to cooperate with the second course when in the second position to divert articles adjacent the diverging section of the second course, the diverter roller being arranged to grip one of the articles against the diverging section of the course spaced

therefrom when in each of its positions trays adjacent the diverging sections of the courses for receiving predetermined numbers of the articles, and means for moving said diverter roller between its positions in response to the count of articles, whereby a predetermined number of articles is counted into each of the trays.

5. A machine for sequestering groups of cylindrical articles of uniform diameter which comprises a pair of continuous belt conveyors having spaced courses with substantially parallel sections spaced sufficiently to engage the articles therebetween for moving the articles longitudinally along the belt conveyors with the articles extending transversely of the belt courses, means for counting said articles while traveling between said courses, said courses having diverging discharge sections, a diverter roller extending transversely of and between said diverging sections, means for mounting said diverter roller for movement longitudinally between a first position spaced from one of the courses and adjacent the second of the courses to divert articles adjacent the first course and a second position spaced from the second course and adjacent the first course to divert articles adjacent the second course, means for rotating the diverter roller in a direction to cooperate with the first course when in the first position to divert articles adjacent the diverging section of the first course and in a direction to cooperate with the second course when in the second position to divert articles adjacent the diverging section of the second course, the diverter roller being arranged to grip one of the articles against the diverging section of the course spaced therefrom when in each of its positions, and trays adjacent the diverging sections of the courses for receiving predetermined numbers of articles, means for moving said diverter roller between its positions in response to the count of articles, whereby a predetermined number of articles is counted into each of the trays, a ram member movable crosswise of each tray, and means for alternately moving the rams through the trays in response to the count of articles to remove articles in an axial direction from one of the trays while articles are diverted toward the other of the trays.

6. A machine for sequestering groups of cylindrical articles of uniform diameter which comprises a pair of continuous belt conveyors having spaced courses with substantially parallel sections spaced sufficiently to engage the articles therebetween for moving the articles longitudinally along the belt conveyors with the articles extending transversely of the belt courses, means for counting said articles while traveling between said courses, said courses having diverging discharge sections, a diverter roller extending transversely of and between said diverging sections, means for mounting said diverter roller for movement longitudinally between a first position spaced from one of the courses and adjacent the second of the courses to divert articles adjacent the first course and a second position spaced from the second course and adjacent the first course to divert articles adjacent the second course, means for rotating the diverter roller in a direction to cooperate with the first course when in the first position to divert articles adjacent the diverging section of the first course and in a direction to cooperate with the second course when in the second position to divert articles adjacent the diverging section of the second course, the diverter roller being arranged to grip one of the articles against the diverging section of the course spaced therefrom when in each of its positions, trays adjacent the diverging sections of the courses for receiving predetermined numbers of the articles, means for moving said diverter roller between its positions in response to the count of articles, whereby a predetermined number of articles is counted into each of the trays, a ram member movable crosswise of each tray, and means for alternately moving the rams through the trays in response to the count of articles to remove articles in an axial direction from one of the trays while articles are diverted toward

the other of the trays, a bucket conveyor adjacent the rams, buckets on the bucket conveyor, and means for advancing the bucket conveyor in response to the count of articles so that a bucket is advanced to a station opposite the rams to receive a predetermined number of articles for each tray.

7. A machine for sequestering groups of cylindrical articles which comprises an article conveyor, said article conveyor having a main course and a downwardly curving discharge section at a discharge end of the main course, means for feeding articles onto the main course of the article conveyor, a pair of belt conveyors mounted adjacent the discharge section, said belt conveyors having spaced courses with substantially parallel sections spaced apart sufficiently to engage and advance articles therebetween, said courses having an article receiving section adjacent the discharge section of the article conveyor, one of said article receiving sections being in closely spaced relation with the discharge section to receive articles from the article conveyor, means for swinging the other article receiving section between a first position sufficiently spaced from the discharge section and the other belt course section to permit entry of an article into the space between belts at the article receiving section and a second position substantially parallel to the article receiving section of the first belt to grip the articles therebetween, means for counting articles as the articles pass between the belt courses, and means for receiving predetermined numbers of articles from said belt courses.

8. A machine for sequestering groups of articles which comprises an article conveyor, said article conveyor having a main course and a downwardly curving discharge section at a discharge end of the main course, means for feeding articles onto the main course of the article conveyor, a pair of belt conveyors mounted adjacent the discharge section, said belt conveyors having spaced courses with substantially parallel sections spaced apart sufficiently to engage and advance articles therebetween, said courses having an article receiving section adjacent the discharge section of the article conveyor, one of said article receiving sections being in closely spaced relation with the discharge section to receive articles from the article conveyor, means for swinging the other article receiving section between a first position sufficiently spaced from the discharge section and the other belt course section to permit entry of an article into the space between belts at the article receiving section and a second position substantially parallel to the article receiving section of the first belt to grip the articles therebetween, and means for counting the articles while the articles are engaged between the belt conveyors.

9. A machine for sequestering groups of cylindrical articles which comprises an article conveyor, said article conveyor having a main course and a downwardly curving discharge section at a discharge end of the main course, means for feeding articles onto the main course of the article conveyor, a pair of belt conveyors mounted adjacent the discharge section, said belt conveyors having spaced courses with substantially parallel sections spaced apart sufficiently to engage and advance articles therebetween, said courses having an article receiving section adjacent the discharge section of the article conveyor, one of said article receiving sections being in closely spaced relation with the discharge section to receive articles from the article conveyor, means for swinging the other article receiving section from a first position sufficiently spaced from the discharge section and the other belt course section to permit entry of an article into the space between belts at the article receiving section and a second position substantially parallel to the article receiving section of the first belt to grip the articles therebetween, one of said belt conveyors including two spaced parallel portions, a counter arm extending through the space between said portions and being engageable by the articles gripped between the belt conveyors, counting means actu-

ated by said counter arm for counting articles as the articles pass between the belt courses, and means for receiving predetermined numbers of articles from said belt courses.

10. A machine for loading a predetermined number of articles into a package which comprises a channel-shaped bucket having a pair of spaced flanges, a base, and an open side, means for advancing the bucket to a loading station with the side flanges extending upwardly, a pair of adjacent trays at the loading station and opposite the open side, means for advancing a wrapper in U-shape into the bucket with a base of the wrapper on the base of the bucket and with sides of the wrapper extending upwardly inside the flanges of the bucket, means for advancing articles in a longitudinal direction alternately into the trays, means for moving articles axially from one of the trays into the bucket onto the wrapper while articles are being counted into the other tray and means for moving articles axially from the other tray into the bucket when articles are being counted into the first tray.

11. A machine for loading a predetermined number of articles into a package which comprises a channel-shaped bucket having a pair of spaced flanges, a base, and an open side, means for advancing the bucket to a loading station with the side flanges extending upwardly, one of said side flanges being pivotally mounted to swing between an upright position and an open position, means for swinging the pivotally mounted flange to open position when the bucket is at the loading station, a pair of adjacent trays at the loading station and opposite the open side, means for advancing a wrapper in U-shape into the bucket with a base of the wrapper on the base of the bucket and with sides of the wrapper extending upwardly inside the flanges of the bucket, means for advancing articles in a longitudinal direction alternately into the tray, means for moving articles axially from one of the trays into the bucket onto the wrapper while articles are being counted into the other tray, means for moving articles axially from the other tray into the bucket when articles are being counted into the first tray, means for advancing the bucket to a second station when the articles have been advanced into the bucket, and means for urging the pivotally mounted flange to upright position when the bucket is advanced to the second station to engage an upstanding portion of the wrapper and fold the wrapper around the articles.

12. A machine for loading a predetermined number of articles into a package which comprises a channel-shaped bucket having a pair of spaced flanges, a base, and an open side, means for advancing the bucket to a loading station with the side flanges extending upwardly, one of said side flanges being pivotally mounted to swing between an upright position and an open position, means for swinging the pivotally mounted flange to open position when the bucket is at the loading section, a tray at the loading station opposite the open side, means for advancing a wrapper in U-shape into the bucket with a base of the wrapper on the base of the bucket and with sides of the wrapper extending upwardly inside the flanges of the bucket, means for advancing articles in a longitudinal direction into the tray, means for moving articles axially from the tray into the bucket onto the base of the wrapper, means for advancing the bucket to a second station when the articles have been advanced into the bucket, and means for urging the pivotally mounted flange to upright position when the bucket is advanced to the second station to engage an upstanding portion of the wrapper and fold the wrapper around the articles.

13. An input conveyor for an article handling machine which comprises a main frame, two pairs of spaced rollers mounted on said main frame, a conveyor belt mounted on each pair of rollers, said conveyor belts having spaced parallel courses adapted to engage and grip articles therebetween, means for driving said conveyor belts with the parallel courses advancing in the same di-

rection and at equal speeds, means for feeding articles to the parallel courses to be gripped and supported thereby, a diverter arm mounted adjacent the belts, and means for moving the diverter arm between a released position outside the path of articles between the belts and an operative position extending between the parallel courses and transversely of the path of articles to divert the articles crosswise of the belts while engaged by the belts to be released therefrom.

10 14. An input conveyor for an article handling machine which comprises a main frame, two pairs of spaced rollers mounted on said main frame, a conveyor belt mounted on each pair of rollers, said conveyor belts having spaced parallel courses adapted to engage and grip articles therebetween, means for driving said conveyor belts with the parallel courses advancing in the same direction and at equal speeds, means for feeding articles to the parallel courses to be gripped and supported thereby a diverter arm pivotally mounted adjacent the belts and 15 means for swinging the diverter arm between a released position outside the path of articles between the belts and an operative position extending between the parallel courses and transversely of the path of articles to divert the articles crosswise of the belts while engaged by the 20 belts to be released therefrom.

15 15. A machine for sequestering groups of articles which comprises a pair of conveyors having spaced courses with substantially parallel sections spaced sufficiently to engage the articles therebetween for moving the articles 30 along the conveyors, said conveyors having diverging discharge portions, a diverter roller extending transversely of and between said diverging portions, means for mounting said diverter roller for movement longitudinally between a first position spaced from one of the diverging 35 positions and adjacent the second of the diverging portions to divert articles adjacent the first diverging portion and a second position spaced from the second diverging portion and adjacent the first diverging portion to divert articles adjacent the second diverging portion, means for rotating the diverter roller in a direction to cooperate with the first diverging portion when in the first position to divert articles adjacent the first diverging portion and in a direction to cooperate with the second diverging portion when in the second position to divert articles adjacent the 40 second diverging portion, and means adjacent each of the diverging portions for receiving the articles.

16 16. A machine for sequestering groups of articles which comprises a pair of conveyors having spaced courses with substantially parallel sections spaced sufficiently to engage the articles therebetween for moving the articles along the conveyors, means for counting said 50 articles while traveling between said sections, said conveyors having diverging discharge portions, a diverter roller extending transversely of and between said diverging portions, means for mounting said diverter roller for movement longitudinally between a first position spaced from one of the diverging portions and adjacent the second of the diverging portions to divert articles adjacent the first diverging portion and a second position spaced 55 from the second diverging portion and adjacent the first diverging portion to divert articles adjacent the second diverging portion, means for rotating the diverter roller in a direction to cooperate with the first diverging portion when in the first position to divert articles adjacent the first diverging portion and in a direction to cooperate with the second diverging portion when in the second position to divert articles adjacent the second diverging portion, and means adjacent each of the diverging portions 60 for receiving predetermined numbers of the articles, and means for moving said diverter roller between its positions in response to the count of articles, whereby a predetermined number of articles is counted into each article-receiving means.
